UNITED STATES PATENT OFFICE.

HERMAN PAUL SACHSE, OF CHICAGO, ILLINOIS, ASSIGNOR TO CENTRAL SCIENTIFIC CO., OF CHICAGO, ILLINOIS, A CORPORATION OF ILLINOIS.

BALANCE.

Application filed February 19, 1923. Serial No. 619,816.

To all whom it may concern:

Be it known that I, HERMAN PAUL SACHSE, a citizen of the United States, and resident of Chicago, in the county of Cook and State of Illinois, have invented a certain new and useful Improvement in Balances, of which the following is a full, clear, concise, and exact description, reference being had to the accompanying drawings, forming a part of this specification.

My invention relates to a laboratory balance of the type comprising pan supporting hangers which are pivotally mounted upon the ends of a centrally pivoted beam, and which are arranged to maintain the pans in horizontal planes, irrespective of the inclination of the beam; the present invention being particularly concerned with certain improvements in the construction of the hangers and their associated parts.

Each of the hangers forming part of the balance herein shown and described is preferably formed in one piece, conveniently by a die casting operation, and is conformed to provide a pocket for shot, which is employed in giving the balance its original adjustment and for correcting its adjustment, when required. These shot pockets are so located that they are at all times accessible, even when the pans are in position upon the hangers, this being a feature of decided advantage because permitting any difference between the weights of the pans employed to be compensated for by the shot, and also permitting the pans to support the shot pocket-closing devices when the shot pockets are opened for the purpose of effecting a proper division of shot therebetween.

These and other features, objects, and advantages of my present invention will appear from the following detailed description, wherein reference is made to the accompanying drawings, in which—

Figure 1 is a top plan view of my improved balance, with one pan removed;

Figure 2 is a front elevational view of the balance;

Figure 3 is a vertical section taken on line 3-3 of Figure 2, and looking in the direction indicated by the arrows, and

Figure 4 is a central longitudinal section, illustrating the shot pockets open, and

the shot pocket-closing devices carried upon the pans.

Similar characters of reference refer to 55 similar parts throughout the several views.

Referring to the drawings, reference character 10 indicates an elongated hollow base which comprises the central pillar 11 and the upwardly projecting hollow bosses 60 12-12 which are located at the ends of the base.

Pillar 11 is bifurcated at its upper end, as indicated at 13, to embrace and support the tilting beam 14, which is conveniently, but not necessarily, cast in one piece. 65

It may be explained that the beam is preferably provided with knife-edge trunnions bearing in V-shaped notches in blocks of suitable bearing material (not shown),

which are cemented in, or otherwise carried 70 by, the upper extremities of the bifurcated portion of the central pillar 11. The devices for pivotally mounting the beam upon the central pillar form no essential part of my present invention, and for that reason 75

have not been illustrated in detail.

Carried by one of the upper extremities of the pillar 11, and projecting upwardly and forwardly therefrom, is a metal plate 15 which, at its upper end, is provided with 80

a deflection scale 16 with which cooperates a pointer 17, the latter being fixed to the beam 14 at its central point. The pointer 17 is preferably struck from sheet metal and, as here shown, carries a screw 18 whereon

is mounted a nut 19 which, by adjustment 85 relative to the axis of the beam, may be utilized to make minor corrections, in the

proper division of shot therebetween.

Disposed within the hollow base 10 and 90 conveniently anchored in the pillar 11 is a screw 20 having a bifurcated lower end to which are pivoted the adjacent ends of a pair of links 21-21, the other ends of said links being pivoted to the lower ends of the 95 hangers presently to be described.

Beam 14 is provided with a pair of forwardly projecting bosses 22 whereon is mounted the usual graduated scale 23 upon which a balancing weight 24 is a slidably 100 mounted.

As thus far described, my improved balance need not differ materially in construction from generally similar balances

well known prior to the advent of my present invention.

I shall now proceed to describe the improved hangers which embody the salient features of the present invention. Each of the hangers, illustrated as a whole at 25, is preferably formed in one piece by a die casting operation, and comprises a circular cup 26 provided with an internally threaded central boss 27. Projecting downwardly from the cup 26 is an arm 28 which, when the balance is assembled, extends through one of the hollow base bosses 12 and has its lower end pivotally attached to one of the links 21-21, to which reference has previously been made (see Figures 3 and 4). Diverging upwardly from the cup 26 are the arms 29-29 which, at 30-30, are recessed to receive blocks 31-31 of suitable hard material, the blocks 31-31 being provided with downwardly opening V-shaped notches 32 for co-operation with the upwardly presented edges of bearing trunnions 33-33 which project laterally from and are formed integral with the beam 14.

It will thus be seen that each of the hangers is pivotally mounted upon one end of the beam, but is at all times held in a substantially vertical position, regardless of the inclination of the beam, by virtue of its associated link 21. The arms 29-29 terminate in the pan support 34 which has a flat upper surface 35, is preferably apertured at 36, and is provided with four radial ears 37-37, each of which is provided on its under side with a rib 38. Embracing each of the ribs 38 is a bifurcated clip 39 provided with an upturned outer end adapted to embrace the periphery of a pan 40 which rests upon the upper surface 35 of the pan support. The clips 39 are held in adjusted position by screws 41. Pans 40 are preferably circular and of uniform thickness, and may be formed of porcelain, glass, or other suitable material.

Each of the hanger cups 26 constitutes a receptacle for a quantity of shot illustrated at 42. The said cups or shot receptacles are normally closed by centrally apertured discs 43 which find suitable seats in the cups and are held in position by screws 44 engaging in the internally threaded bosses 27.

It will be noted that the cups 26 are readily accessible even when the pans 40 are fixed upon the hangers. This is a feature of decided advantage. In prior balance constructions wherein shot has been employed as a means for compensating for differences between the aggregate weights of those parts of the balance carried upon opposite sides of the beam pivot, it has always been necessary to take the weight of some normal part of the device off the beam in order to obtain access to the shot pockets. Thus, in certain

prior constructions, it has been necessary to remove the pans in order to obtain access to the shot receptacles. Such constructions are disadvantageous because the removal and replacement of the pans involve considerable loss of time, and are further disadvantageous because no distribution of shot with the pans removed can compensate for a difference between the weights of the pans.

In utilizing the shot properly to adjust my improved balance, the discs 43 and screws 44 are merely removed from the cups 26 and are placed upon the pans 40, as is clearly illustrated in Figure 4. With the nut 19 occupying the central position upon screw 18, the beam is brought to a perfect balance by a proper distribution of shot between the cups 26. The discs 43 and screws 44 may then be replaced with the assurance that the balance of the instrument will not be disturbed by the replacement of these parts, notwithstanding the fact that the combined weight of the disc and screw applied to one of the cups may differ from the combined weight of the disc and screw applied to the other cup.

Having thus illustrated and described my invention, what I claim is new and desire to secure by Letters Patent of the United States is:

1. In a balance and in combination, a beam pivoted intermediate its ends for movement around a horizontal axis; hangers carried upon the ends of said beam; each of said hangers comprising a cup located a substantial distance below the beam, a pair of separated arms rising from said cup, embracing the adjacent end of the beam and extending above the latter, said arms being pivoted to said beam and having their upper ends connected by a pan support; pans disposed on the pan supports; closures for the hanger cups adapted to be removed therefrom and to be placed upon the pans when the instrument is adjusted by distributing shot between said cups; each hanger comprising an arm extending downwardly from the cup portion thereof; and links connected with said last mentioned arms adapted to maintain said pans substantially horizontal regardless of the inclination of the beam.

2. In a balance and in combination, a beam pivoted intermediate its ends for movement around a horizontal axis; hangers associated with the ends of said beam; knife-edge pivot devices whereby said hangers are pivoted to said beam; each of said hangers comprising a pair of vertically extending arms lying on opposite sides of the beam and extending above and below the latter, a pan support overlying the beam and formed integral with said arms, a shot cut lying a substantial distance below the beam and formed integral with the lower ends of said arms, a removable closure for

- said cup; pans carried by the pan supports; and links co-operating with said hangers adapted to maintain said pans substantially horizontal regardless of the inclination of the beam.
5. 3. In a balance and in combination, a beam pivoted intermediate its ends for movement around a horizontal axis; a pair of pans disposed over the extremities of said beams;
- 10 4. a pair of hangers by which said pans are carried; each of said hangers comprising a pan support, three arms, and a shot receptacle, all formed in one piece, the pan support lying above the beam, two of the
- 15 arms extending downwardly from the pan support alongside the beam and being pivoted to the latter for relative movement around a horizontal axis, said arms extending a substantial distance below the beam
- 20 and joining the shot cup, the other arm extending downwardly from the shot cup; removable closures for said shot cups; and means associated with those hanger arms
- which project downwardly from the shot cups adapted to maintain the pan supports substantially horizontal regardless of the inclination of the beam.
- 25
4. In a balance, a beam pivoted intermediate its ends for movement around a horizontal axis, pans disposed over the extremities of said beam, and means for supporting said pans comprising a pair of hangers, each pivoted to one end of the beam, and each provided with a shot pocket wholly located beneath the beam, closures for said shot pockets also wholly located beneath the beam, said closures being independent of the pans and accessible for removal without removing the hangers from the beam or the pans from the hangers.
- 30
- 35
- 40
- In witness whereof, I hereunto subscribe my name this 14 day of February, 1923.
- HERMAN PAUL SACHSE.
